Attorney.

UNITED STATES PATENT OFFICE.

CHARLES A. OTT, OF LINCOLN, RHODE ISLAND.

SAFETY STOP DEVICE FOR STATIONARY STEAM-ENGINES.

SPECIFICATION forming part of Letters Patent No. 762,249, dated June 7, 1904.

Application filed October 31, 1903. Serial No. 179,398. (No model.)

To all whom it may concern:

Be it known that I, CHARLES A. OTT, a citizen of the United States, residing at the town of Lincoln, in the county of Providence and State 5 of Rhode Island, have invented certain new and useful Improvements in Safety Stop Devices for Stationary Steam-Engines, of which the following is a specification.

This invention relates to an electrically-actuated valve mechanism adapted to control the steam in a stationary steam-engine; and the object of my invention is to provide an effective device which can be operated upon to instantly shut off the steam from the engine 15 in case of accident in any part of the works.

My invention consists in a spring-controlled valve properly mounted and interposed between the throttle-valve and the steam-inlet pipe of the engine, electrically-actuated means 20 for releasing said spring-controlled valve to close upon its seat, and means for relieving the steam-pressure upon said spring-controlled valve that the same may be moved to its electrically-operated position, of the novel 25 construction and combination of parts, as hereinafter described, and specifically set forth in the claim.

In the accompanying sheet of drawings, Figure 1 represents a side elevation of my 30 electrically-actuated valve as applied to the throttle-valve and steam-inlet pipe of the engine. Fig. 2 is an enlarged central longitudinal sectional view showing the throttle-valve, spring-controlled valve, and steam-inlet pipe, respectively, and said valves open as 35 when the engine is in operation. Fig. 3 is a vertical cross-sectional view taken in line XX of Fig. 2, showing the electrically-actuated mechanism for holding the spring-controlled 40 valve open, as when the engine is running. Fig. 4 is a similar sectional view showing the relative position of parts of the device as 45 when the releasing mechanism has been tripped electrically and the spring has closed the valve upon its seat and shutting off the steam from the engine. Fig. 5 is a top plan view of the casing for the spring-controlled valve and showing a by-pass adapted to relieve the pressure of steam against said valve

when the same is to be opened and held to its 50 normal position.

Like letters of reference indicate corresponding parts in the different views of the drawings.

Referring to Fig. 2, A represents a tubular casing which is divided by a partition b, so as to provide two steam-chambers c and c'. Said partition is provided with a circular beveled opening d, communicating with the chambers of the casing and forming a seat 60 against which a valve-disk e rests in closing the said opening. The valve-disk e is rigidly secured upon a rod e', that projects vertically from the casing, and the lower portion of said rod beneath the said valve-disk e is mounted and 65 movable in a step f, that is secured in the annular flange b' integral of the casing. A push-spring f' surrounds the rod e' and is interposed between the said valve-disk e and said step f. g is a packing-ring interposed 70 between the step f and the annular flange b' of the casing, and a suitable stuffing-box g' surrounds the upper portion of the valve-rod e', said stuffing-box being secured upon a projecting annular flange of the casing. The 75 casing A has an integral upward extension b² at one side thereof, and the upper extremity of said extension is bifurcated to receive the end of a swinging arm h, which is connected to the bifurcated end of the said extension by 80 a pin h'. The upper end of the valve-rod e' is bifurcated to receive the arm h, and a pin h², rigid in the bifurcated end of the valve-rod, loosely enters an elongated slot h³, formed in the said arm h, as shown in Fig. 3. At the opposite side of the casing A and integral therewith is another upward extension b³, whose upper extremity has a fixed stud b⁴, upon which is loosely mounted a latch-lever i. Said lever has a tongue projection i' at its upper end to 90 engage upon the end of the arm h in holding the valve-disk e open or in its normal position, as seen in Fig. 3. b⁵ is an outer extension integral of the casing A and arranged to support the electromagnets j j. k is a lever having an armature to contact with the amatures of the magnets j j, and this armature-lever k has a tongue k' to engage a hook i², formed on 95

the lower end of the latch-lever *i*. This valve-casing *A*, with the tripping mechanism for actuating its valve, as described, is adapted to be interposed between the casing *l* of the ordinary throttle-valve of a stationary steam-engine and the steam-inlet pipe *m*, said valve-casing *A* being fixedly secured in position by bolts *n n*, which enter through an outer annular flange integral at each end of the said valve-casing *A* and through the corresponding annular flange of the throttle-valve casing *l* and steam-pipe *m*, respectively, in the manner as shown in Fig. 2.

Referring to Fig. 1, *o* represents an electric push-button fixedly secured in a wall of the factory or works, and this button has the usual armature from which a wire *q* leads to the positive pole of a storage battery *q'*, and from the negative pole of the battery a wire *q''* leads to one of the electrically-connected magnets *j*. From the other electromagnet a wire *q'''* leads back to the armature of the push-button *o*. When the throttle-valve *l* and valve *e* are open, as shown in Fig. 2, the steam passes through from the inlet-pipe *m* in the arrow-direction to the steam-chest of the engine, and as the engine is running the parts which hold the valve *e* open are in the position as shown in Fig. 3. Now if perchance an accident should happen in some part of the factory or works remote from the engine-room as should require the stoppage of the engine, by simply pressing on the push-button *o* causes the electromagnets *j j* to attract the armature of the lever *k*, which when carried down by the magnets disengages itself from the hook of the latch-lever *i*. A pull-spring *s*, whose ends are connected to the casing *A* and latch-lever *i*, draws back the latter from engagement with the arm *h*, and at this moment the push-spring *f'* instantly forces the valve *e* upon its seat *e'* to the position of parts as indicated in Fig. 4, thus shutting off the steam from throttle-valve and causing the engine to cease running.

Any number of push-buttons may be located at convenient intervals in the factory and connected with the device, and by having a spring-pressed valve intermediate of

the throttle-valve and the steam-pipe and electrically actuated, as described, the power is placed under constant and instantaneous control from the most remote point in the factory or shop. To reduce the steam-pressure against the bottom of the valve-disk *e*, so that the same may be forced back and held in its normal position, as indicated in Fig. 3, I provide a by-pass *t*, which communicates with the chambers *c* and *c'* of the casing, as seen in Figs. 2 and 5, and said by-pass has a valve *u* for the engineer to close after the valve *e* has been adjusted to its open position.

Having described my invention, what I claim, and desire to secure by Letters Patent, is—

In a safety-stop for stationary steam-engines having a steam-inlet pipe and a throttle-valve, the combination, of a device comprising a fixed tubular casing communicating with said inlet-pipe and said throttle-valve and divided by a partition having a port; a by-pass communicating with the said casing at each side of its partition; a movable rod projecting from said casing, and carrying a valve-disk arranged to close the port in the same; a push-spring interposed between said valve-disk and the said casing; an arm pivoted on an extension of the casing, and connected to the valve-rod of the same; a latch-lever pivoted on a support of the casing and having a hook at one end and a lug at its opposite end thereof to engage the free end of said arm; a pull-spring from the hook portion of said latch-lever to said casing; a lever pivoted on a support of the casing and provided with an armature arranged at one end and a tongue at its opposite end thereof to engage the hook of said latch-lever; electromagnets arranged to attract the armature of said lever, and a push-button electrically wired to said magnets, substantially as shown and for the purpose specified.

In testimony whereof I affix my signature in the presence of two witnesses.

CHARLES A. OTT.
